LEVER LOCK MECHANISM

John C. Wahl, Chicago, Ill., assignor to Lion Manufacturing Corporation, Chicago, Ill., a corporation of Illinois

Application September 7, 1938, Serial No. 228,763

14 Claims. (Cl. 192—116.5)

The invention relates to lever lock mechanism.

In coin operated vending and amusement machines of the type having a cabinet with interior operating mechanism which is manually initiated into operation upon swinging movement of an exterior lever, it sometimes happens due to jamming or failure of the operating mechanism properly to function, that under such circumstances the operator will bear down on the lever with considerably more than the normal force required to operate the mechanism from the lever. When this happens breakage and damage of the interior operating mechanism results and the machine is put out of order, necessitating expensive repairs.

The main object of this invention is to provide an improved lever lock mechanism which will function automatically under the above mentioned circumstances of abnormal resistance, to take the load of the lever off the operating parts to prevent same from being damaged.

Another object is to provide a simple and effective mechanism for the purposes stated.

Other important objects will become apparent to those versed in this art as the disclosure is more fully made.

These desirable objects may be achieved by the illustrative example herein chosen for purposes of the disclosure in which form a coin operated machine has a cabinet and a wall thereof carries the fulcrum for an exteriorly located hand lever movable through an arc to operate parts on the inside, reinforced, face of the wall, said parts in turn operating means to rock a shaft of the interior operating mechanism of the coin operated machine. In the event something goes wrong with the interior operating mechanism and a greater than normal resistance is set up against its operation through the rock shaft by the hand lever, then a lock means operatively associated with the lever parts comes automatically into play to lock the lever to the reinforced wall to prevent its further movement, no matter how hard the operator may force same. In this manner the coin operated machine is saved from damage.

The improved mechanism, in one practicable form, is shown in the accompanying sheets of drawings, wherein:

Figure 1 is a general inside face elevational view of the improved lever mechanism as viewed generally from the line 1—1 of Figure 3;

Figure 2 is a view similar to Figure 1, but showing the lever in locked position;

Figure 3 is a vertical view through the mechanism, taken along the line 3—3 of Figure 2, looking in the direction of the arrows;

Figure 4 is a detail sectional view taken along the line 4—4 of Figure 2, looking in the direction indicated; and,

Figure 5 is a detail elevational view of the lever bearing fulcrum member.

The coin operated machine with which the invention may be used has a cabinet 10 including a side wall 11, the inner face of which is suitably reinforced by a metal plate 12 fastened thereto. A large horizontal circular opening 13 is formed in the wall 11 and plate 12 in which opening is journaled a cylindrical bearing or fulcrum part 14 projecting a substantial distance beyond the outer face of the wall 11 where it is surrounded by a collar member 15 secured to the wall, as shown. The outer end of the bearing cylinder 14 has two diametrically opposed bosses 16 extending therefrom, which fit into corresponding openings in the fulcrum end of a hand lever 17. At the points mentioned the lever will be securely welded to the part 14 so that in practice they may rock as one integral unit.

The opposite end of the bearing 14 extends slightly through the plate 12 where it has other bosses 18 to fit into openings of complementary shape formed in a lever arm 19, these parts also being connected by welding so that the arm 19 rocks with the lever 17. A cap 20 is placed over the outside of the lever fulcrum 17 by means of a screw bolt 21, a nut 22 being provided on the inside face of the lever arm 19 securely to clamp the parts together. Thus the lever 17, cylinder bearing 14, and lever arm 19 are a functionally integral unit journaled in the wall opening 13, the cap 15 and the aligned opening in the reinforcing plate 12.

The coin operated machine parts in the interior of the cabinet may be of any desired form, in the present instance taking the form of a horizontal rock shaft 23 journaled in a wall 24. This shaft projects through the wall and on its end proximate the wall 11, said shaft has a lever arm 25 fixed thereon, the arm in turn fixedly carrying a pin 26.

Going back now to the lever arm 19, it will be seen that a pull spring 27 is connected to an ear thereof, the other end of the said spring being suitably anchored to the plate 12, as shown. Said arm 19 has an upper stop boss 28 and a lower stop boss 29 formed thereon so that as the arm 19 swings about the axis of the bearing 14, these bosses may engage rubber cushion blocks 30 respectively anchored in brackets 31 rigidly mounted in angularly disposed positions on the plate 12. In this fashion limits are provided for the swinging movement of the lever 17. The spring 27, of course, normally holds the lever unit structure comprising parts 17, 14 and 19 in the position shown in Figure 1.

Between the stop blocks 30, the plate 12 has securely fastened thereto a strong toothed member in the form of an arcuate rack bar 32. Ad-

jacent the lower boss 29 the lever arm 18 carries a pin 33 on which is freely pivoted a dog 34 having a hole 35 formed therein to receive a pin 36 of much smaller diameter, said pin being carried on the lever arm 19. By means of the structure described the dog 34 hangs by gravity on the pin 36 as shown in the drawings in which position the point of the dog 34 stays clear of the teeth on the rack bar 32. In the event the lever 17 is very suddenly, or too quickly swung clockwise, as shown in Figures 1 and 2, the dog by inertia is caused to engage in the teeth of the rack bar 32 and lock the lever 17 against further movement, thereby preventing the lever 17 from being used suddenly to shock or jar the interior parts, thus saving same from being damaged. Under such circumstance the operator must release the lever 17 to free the dog 34 and start the lever operation over again.

The lever arm 19 at substantially a central point is formed with a circular opening 37 (see Figure 4) with which is concentrically formed a countersunk circular depression 38, as shown. In the opening 37 is located a pivot pin 39 of much smaller size than the opening 37 so that the pin may move bodily in the opening. The pin has a large cap 40 to guide the pin and hold it in the opening 37, said cap being seated in the depression 38 and cooperating with the edge of the depression to act as a stop. Said pin 39 is riveted into an irregularly shaped lever 41 which as seen in Figures 1 and 2 has a tail portion 42 pulled by a spring 43 connected to a pin 44 mounted on the lever arm 19. This spring thus normally holds the pin 39 with its cap 40 over to the left as viewed in Figure 1.

The auxiliary lever 41 has an upstanding portion and an angularly extending portion 45 terminating a toothed foot 46 positioned proximate the rack bar 32. The portion 45 carries two spaced rigid transverse pins 47 and secured to the pins is a rigid driver bar 48 adapted to engage the pin 26 heretofore described for rocking the arm 25 and shaft 23. This completes the details of the structure and the operation thereof will next be described.

The normal starting position of the parts is shown in Figure 1. The operation of the inertia pawl or dog 34 and its purpose has already been described and will not be repeated. The spring 27 normally holds the lever arm 18 with the bearing 14 and main hand lever 17 rocked back to the positions thereof shown in Figure 1. The spring 43 acts to hold the auxiliary lever 41 over to the left because of the slideable pivot 39 provided therefor. In normal operation the hand lever 17 is slowly swung clockwise as viewed in Figures 1 and 2. Presently the driver bar 48 engages the pin 26 to rock the member 25 and the shaft 23 to operate the coin machine. When this happens the toothed shoe 46 clears the rack bar 32 and skirts same without making engagement therewith. In the event, however, that something has gone wrong with the driven parts 23, 25 and the resistance therefrom transmitted to the driver bar 48 is greater than normal, then the resisting force will raise the extension 45 of the lever 41 to move the auxiliary lever 41 relative to the lever 19. In other words, the spring 43 gives and the pivot pin 39 shifts in the opening 37 to occupy the right hand position shown in Figures 2 and 4. Obviously, in this position, the toothed shoe 46 has moved sufficiently to engage and lock with the toothed bar 32 whereby positively to prevent further movement of

the lever 17. The lever 17 cannot now be forced and the interior operating mechanism of the machine will be saved from damage. In the normal operation the cushion blocks 30 save the parts from shock in an obvious manner.

It can now be seen that an improved lever lock mechanism has been provided for the purposes stated. The intention is to cover all such changes and modifications as do not in material respects constitute departures from the spirit and scope of the invention as covered in the appended claims.

What is claimed is:

1. In a lever mechanism for operating a rockable part, said mechanism comprising a support, a functionally integral unit carried in the support for rocking movement and comprising a hand lever, a bearing and a lever arm, with the support carrying the bearing and the lever and arm disposed on opposite sides thereof, a toothed bar rigidly positioned on the support, an auxiliary lever, means carrying the latter lever for relative movement on the arm, driver means on the auxiliary lever to engage and operate the rockable part, and a lock means associated with the auxiliary lever and engageable with the toothed bar to lock the unit against movement when resistance of the rockable part causes movement of the auxiliary lever to engage its lock means with the toothed bar.

2. In a lever mechanism for operating a rockable part, said mechanism comprising a support, a functionally integral unit carried in the support for rocking movement and comprising a hand lever, a bearing and a lever arm, with the support carrying the bearing and the lever and arm disposed on opposite sides thereof, a toothed bar rigidly positioned on the support, an auxiliary lever, means carrying the latter lever for pivotal and bodily shifting movement on the arm, driver means on the auxiliary lever to engage and operate the rockable parts, and a lock part included in the auxiliary lever and cooperable with the toothed bar to lock the unit against movement when resistance of the rockable part causes pivotal and shifting movement of the auxiliary lever to engage its lock part with the toothed bar.

3. In a lever mechanism for operating a rockable part, a support, a lever fulcrumed on the support, an arm movable with the lever, an auxiliary lever carried on the arm for relative movement with respect thereto, a notched member on the support, means to operate the rockable part from the auxiliary lever, and a part on the auxiliary lever movable therewith to engage the notched member and lock the first lever against movement when resistance of the rockable part is sufficient to cause relative movement of the auxiliary lever.

4. In a lever mechanism for operating a rockable part, a support, a lever fulcrumed on the support, an arm movable with the lever, an auxiliary lever carried on the arm for pivotal and shifting movement with respect thereto, an arcuate rack bar rigidly carried on the support, means to engage and operate the rockable part from the auxiliary lever, and a toothed part on the auxiliary lever movable therewith to engage the rack bar and lock the first lever against movement when resistance of the rockable part is sufficient to cause pivotal and shifting movement of the auxiliary lever.

5. In a lever mechanism for operating a rockable part, a support, a lever fulcrumed on the

- support, an arm movable with the lever, an auxiliary lever carried on the arm for relative movement with respect thereto, a lock member rigid on the support, means to operate the rockable part from the auxiliary lever, resilient means to hold the auxiliary lever against movement relative to the arm, and a lock part movable with the auxiliary lever cooperable with the lock member to lock the first lever against movement when 5 resistance of the rockable part is sufficient to cause relative movement of the auxiliary lever.
6. In a lever mechanism, a support, a lever fulcrumed thereon, an arm movable therewith, an auxiliary lever carried on the arm, said auxiliary lever adapted to engage and operate a rockable part, means enabling the auxiliary lever to have pivotal and shifting movement relative to the arm, spring means holding the auxiliary lever normally against movement with respect to the 10 arm, and means to lock the first lever against movement when the auxiliary lever has relative movement with respect to the arm resulting from more than normal resistance of the rockable part to operation by the auxiliary lever.
15. 7. In a lever mechanism, a support, a lever fulcrumed thereon, an arm movable therewith, an auxiliary lever carried on the arm, said auxiliary lever adapted to engage and operate a rockable part, means enabling the auxiliary lever to have pivotal and shifting movement relative to the arm, spring means holding the auxiliary lever normally against movement with respect to the arm, and cooperable parts on the auxiliary lever and support to lock the first lever against movement when the auxiliary lever has relative movement with respect to the arm resulting from more than normal resistance of the rockable part to operation by the auxiliary lever.
20. 8. In a lever mechanism, a support, a lever fulcrumed thereon, an arm movable therewith, an auxiliary lever carried on the arm, said auxiliary lever adapted to engage and operate a rockable part, means enabling the auxiliary lever to have movement relative to the arm, means limiting such movement, means yieldably holding the auxiliary lever against such relative movement, and cooperable parts on the auxiliary lever and support to lock the first lever against movement when the auxiliary lever has relative movement with respect to the arm resulting from more than normal resistance of the rockable part to operation by the auxiliary lever.
25. 9. In a lever mechanism, a support, a horizontal bearing in the support, a hand lever and lever arm rockable together about the bearing axis, said arm having opposite bosses thereon, brackets on the support disposed in spaced relation on an arc, cushions in the brackets cooperable with the bosses to limit the swing of the lever and arm, an auxiliary lever carried on the arm for movement about a sliding pivot, an arcuate rack bar on the support, a toothed part on the auxiliary lever to cooperate with the rack bar, a spring to pull the auxiliary lever normally to keep the toothed part away from the rack bar, and a driver on the auxiliary lever to thrust against rockable parts to operate same, said driver when resistance from the rockable parts is greater than normal acting to shift the auxiliary lever and engage the toothed part with the rack bar to lock the lever against movement.
30. 10. A lever mechanism comprising a lever arm fulcrumed on a horizontal axis in a support, an irregularly shaped auxiliary lever carried on the arm for pivotal and shifting movement, said arm including a toothed part, a complementary part rigid on the support, a driver part carried on the auxiliary lever spaced from the toothed part, said driver part adapted to engage proximately disposed rockable parts, a spring pulling the auxiliary lever, means to limit swinging movement of the arm means to limit relative movement of the auxiliary lever, the toothed part moving with the auxiliary lever when resistance to the driver part exceeds normal, to cause engagement of the toothed part with the complementary part to lock the lever.
35. 11. A lever mechanism comprising a lever arm fulcrumed on a horizontal axis in a support, an arm movable therewith, means to limit the arc of movement of the arm, an arcuate toothed rack bar carried on the support adjacent the arm, and an inertia dog carried pivotally for limited relative movement on the arm and adapted to engage the rack bar and lock the lever mechanism against movement when the latter is moved too rapidly.
40. 12. In a lever mechanism, a support structure, a lever fulcrumed thereon, an arm movable therewith, an auxiliary lever, means carrying the auxiliary lever for movement with and for independent movement relative to said arm, said auxiliary lever being positioned adjacent a movable part and adapted to engage and move said movable part, yieldable means normally to prevent relative movement of the auxiliary lever with respect to the arm, a stationary lock member associated with the support structure, and a cooperable lock part operatively associated with the auxiliary lever and serving when the auxiliary lever moves relative to the arm against the yielding means as the result of abnormal resistance from the movable part to engage the lock member and prevent further movement of the lever.
45. 13. In a lever mechanism for operating a movable part, a support structure, a hand lever fulcrumed on the support structure, an arm movable with the lever, an auxiliary lever, means carrying the auxiliary lever for movement with and for independent movement relative to said arm, said auxiliary lever being positioned adjacent the movable part so that it is adapted to engage and operate same, a lock member rigidly included in the support structure, a yieldable connection between the arm and auxiliary lever normally to prevent relative movement of said parts, and a lock part associated with the auxiliary lever and serving when the auxiliary lever moves relative to the arm against the yieldable connection as the result of abnormal resistance from the movable part to engage the lock member and prevent further movement of the hand lever.
50. 14. Lever mechanism comprising a lever fulcrumed in a support, an arm in the form of a plate rockable with the lever, an irregularly shaped auxiliary lever generally in the form of a bell crank pivotally carried at its angle on the plate, said auxiliary lever having a tail, a spring connected between the plate and tail, the other leg of the auxiliary lever including a driver bar part and an extended lock part, and means for connecting an intermediate portion of the tail part to said plate for limited relative movement.
